[57] CLAIM

The ornamental design for a data processor, as shown and described.

DESCRIPTION

FIG. 1 is a front, top, right perspective view of a data processor incorporating our new design.

FIG. 2 is a rear elevational view thereof.

FIG. 3 is a bottom plan view thereof.

FIG. 4 is a left side elevational view thereof.

The left side of the processor shown in FIGS. 1-3 is identical to the right side shown in FIG. 1, except that the switch at the rear of the right side in FIG. 1 is absent from the left side, the latter side thus being entirely blank.

FIG. 1

FIG. 2

FIG. 3

FIG. 4
